UNITED STATES PATENT OFFICE.

DANIEL KNOWLES, OF NORFOLK, VIRGINIA.

TOY.

SPECIFICATION forming part of Letters Patent No. 578,491, dated March 9, 1897.

Application filed July 3, 1896. Serial No. 598,023. (No model.)

To all whom it may concern:

Be it known that I, DANIEL KNOWLES, a citizen of the United States, residing at Norfolk, in the county of Norfolk and State of Virginia, have invented certain new and useful Improvements in Toys; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a perspective view of my improvements. Fig. 2 is a side elevation and partial section of the bat. Fig. 3 is a sectional view on the line $x-x$ of Fig. 2, showing the dart in position in the holder on the bat. Fig. 4 is a perspective view of another form 20 of dart. Fig. 5 is a perspective view showing the bat in position for striking the dart.

In the drawings, A designates a bat provided at one end with a handle A'. As shown, the bat is formed from a single piece of wood or other suitable material and has the body portion thereof widened out to form a relatively large surface.

B designates the dart, which may be made of any suitable material and of any of several forms. In the drawings I have illustrated it as made substantially conical and as provided with a weight d at its smaller end. To the dart are secured feathers or guiding-blades C', which serve to direct the flight of the dart 35 when propelled by a blow from the bat.

On the bat A, I secure a receptacle or holder B, having a socket adapted to receive the body portion of the dart D. This receptacle or holder is shown as being attached to the body 40 of the bat by means of screws b, but may be secured in any other desired and suitable manner. To insure that the dart will be held in position when within this holder, I prefer to provide an annular elastic or yielding ring C, which is firmly secured to the upper edge 45 of the holder B and preferably projects slightly over the socket therein.

In using my improved toy it is intended that the player shall dislodge the dart from 50 its position in the holder B, and after keep-

ing it in motion by striking it with the side of the bat opposite the holder B a number of times (see Fig. 5) shall cause the dart to again seat itself in the said holder.

Preferably I provide the dart with a bell E. 55 In the forms shown in Figs. 1 and 3 this bell is loosely connected to the dart, it having a ring e, which is engaged with a staple d', secured in the bottom of a socket formed in the larger end of the body of the dart. 60

In Fig. 4 I have shown a modified form of dart. In this form a rod F is extended out from the larger end of the dart, the bell E being fitted around said rod, and to the outer end of this rod are secured a series of cords 65 f, the other ends of which are connected to the body of a small parachute G. It will also be seen that two of the devices herein described can be used in the playing of a game of the general character of that known as 70 "battledore and shuttlecock." In such case each of two players is provided with one of the bats and use is made of one, two, or more darts, the latter being, as will be observed, shuttlecock-like in their action; but the 75 game and the devices therefor differ materially from the ordinary battledore and shuttlecock in that it is requisite to catch the dart or shuttlecock in a certain specific manner and at one particular point. 80

By having the cup or socket formed with a conical cap and correspondingly shaping the body part of the dart I provide, first, for guiding the dart readily in the socket, and, second, for having it fit comparatively snugly; but 85 the cavity is somewhat larger at the upper part than the body of the dart, so as to avoid the latter being wedged tightly in place.

What I claim is—

1. A toy consisting of a bat, a holder or receptacle secured to one side of said bat, a yielding ring secured about the open end of said holder, and a dart adapted to fit within said holder and be held therein by the said ring, substantially as set forth. 90

2. A toy consisting of a bat having on one side a plane face, whereby it is adapted for use in striking, and having on the opposite face a cup or socket, and a dart or projectile adapted to be propelled by a blow from the 100

plane side of the bat and to be seated within the said cup, substantially as set forth.

3. A toy consisting of a bat having a holder or receptacle with a conical cavity, and a dart, 5 conical in form and narrower at its larger end than the wider part of the cavity in the holder, substantially as set forth.

In testimony whereof I affix my signature in presence of two witnesses.

DANIEL KNOWLES.
